UNITED STATES PATENT OFFICE

2,575,779

ELECTRICIAN'S WRENCH AND REAMER

Pierre W. Young, Glenview, Ill.

Application March 25, 1950, Serial No. 151,849

4 Claims. (Cl. 7—14.1)

2

The principal object of this invention is to provide a combined wrench and reamer for use in installing house wiring that will reach and turn a nut on a connector in any part of a junction box and will remove burrs from thin-wall tubing and connectors, and which, in a preferred form of embodiment, may be used to perform both operations simultaneously.

Generally speaking, this is accomplished by combining spaced prongs for turning the nut with reamers between and adjacent to the inner side of the prongs.

In the drawings:

Fig. 1 is a perspective view showing the combined wrench and reamer applied to a connector for a piece of wiring conduit and a junction box;

Fig. 2 is a section through a connector, a portion of a junction box, and the end portion of electric conduit;

Fig. 3 is a plan view of the combined tool and reamer; and

Figs. 4 and 5 are plan and end elevations showing the application of the tool to the end of a piece of conduit.

In Fig. 1, there is shown a familiar form of junction box having a wall or bottom 10 and four flanges 11, each provided with a plurality of knock-outs 12 for providing openings to receive wiring conduits 13.

In Fig. 2, there is shown a familiar form of connector including a nipple 14 having a threaded portion 15 adapted to be received in one of the openings of the junction box and made fast by a nut 16. The connector also includes an extension 17 having an enlarged bore or opening 18 to receive the end portion 19 of a conduit.

The wall 10 of the junction box has five knock-outs and each flange 11 has three knock-outs, any one or any number of which may be removed to make an opening or openings to receive the conduits. The position of the openings indicated in Fig. 1, considered with the form of the connector shown in Fig. 2, will be sufficient to indicate that the nuts 16 may be very close together and to the top 11 of the junction box and an adjacent connector.

The conduits are commonly made of what is known as "thin-wall" tubing, which is cut to length by a hacksaw, and hence has burrs inside and outside at the cut end. The connectors are not so subject to the formation of burrs, but frequently have them. Any burr interferes with the threading of the insulated wire into the conduit, and may so injure the insulation as to give rise to a short circuit.

The workmen in many parts of the country do a great deal of installation during inclement weather, and in almost all cases, whether inclement or not, they wear gloves to protect their hands. These conditions increase the difficulty of installing the connectors, and the common way of setting up the nut 16 is with a screwdriver as a driving tool and a hammer to apply the force.

The combined wrench and reamer embodying this invention in this preferred form includes a flat bar 20, here shown as reduced in the intermediate portion to form a handle, and incidentally a tool head 21 at each end.

Each tool head includes spaced prongs 22, rounded on their inner faces 23 and set apart so as to readily straddle the nut 16 and fit the rounded openings or scallops 24.

At what may be called the base of each prong 22 on the inner side adjacent to its inner end, there are formed reamers 25, here shown as composed of V-shaped cutting surfaces 26 and 27, though they may be more nearly U-shaped than V-shaped.

Looking at the left end of Fig. 3, the upper reamer 25 has its V-shaped surfaces 26 and 27 sloped from the near face of the wrench outwardly toward the remote face of the wrench, and those at the lower side of the same head are the reverse. By that arrangement the reamers are set to cut on substantially diametrically opposite portions of a conduit or a connector.

Between the prongs 22 and equally spaced from them and endwise from the reamers is a center projection 30, rounded at its edges 31 to fit the interior of the connector with appropriate clearance.

The combined tool and reamer has a head such as described at each end, but the one at the right in Fig. 3 and at the top in Fig. 1 is turned at right angles to the main body of the tool.

With this arrangement, one of the heads can be applied to a connector in any position in the junction box shown in Fig. 1 or any other in common use, and with appropriate movement the nut 16 can be turned to set it up or release it as the case may be. Any conflict with adjacent nuts or adjacent connectors is such as to permit necessary rotation, at least in small portions of a turn.

In reaming the burrs from the ends of conduit cut by a hacksaw or otherwise, the tool head is applied substantially as shown in Fig. 4, pressed against the end of the conduit and ro-

tated clockwise with the reamer edges as shown. The points of the V-shaped reamers 25 are spaced just right to apply the cutting edges inside and outside of the conduit, and therefore will remove burrs on both sides at the same operation. The centering portion 30 assists in entering the tool, but after it has reached the position shown in Fig. 4 the reaming edges serve to center themselves. Hence, the portion 30 may be reduced or eliminated.

In applying the tool as shown in Fig. 1 or with the other end spanning the connector, the reaming surfaces will take any burrs off the nipple 15 at its end portion within the junction box, and the centering projection 30 will clear anything in the connector beyond the end of the conduit.

As shown in Fig. 1, the reaming and tightening operations may be performed simultaneously. This is possible because it is standard practice of the manufacturers to make the nipples 14 of uniform length, or at least of standard uniform length between the shoulder which abuts the outer surface of the junction box and the end of the nipple inserted in the box. The standard box also has walls of uniform thickness. Consequently it is a simple matter to make the depth of the openings between the prongs 22 and the centering projection 30 of the tool appropriate for causing the cutting edge or edges 26 to make reaming engagement with the end of the nipple while the nut is being led into tight engagement with the box wall.

It is customary to fasten the junction boxes, measure the conduit, cut it to length, slip the connectors over the ends of the conduit, crimp them, and then make necessary insertions in the holes formed by removing the knock-outs 12 and apply the nuts. All the workman needs is the crimper and the combined wrench and reamer of this invention.

I claim:

1. In a combined wrench and reamer, a head having a pair of laterally spaced openings open to one end of the head, a cutting edge at the

base of each opening, a pair of prongs each projecting endwise beyond one of said edges for cooperating to straddle a nipple and a nut thereon and engage projections on the nut, and a centering projection between the prongs adapted to enter the nipple and guide the head thereon.

2. In a combined wrench and reamer, a head having a pair of laterally spaced openings open to one end of the head, a pair of intersecting cutting edges at the base of each opening, a pair of prongs each projecting endwise beyond one of said edges for cooperating to straddle a nipple and a nut thereon and engage projections on the nut, and a centering projection between the prongs adapted to enter the nipple and guide the head thereon.

3. In a combined wrench and reamer, a flat bar terminating at one end in a head having a pair of laterally spaced openings open to one end of the head, a pair of cutting edges, one at the base of each opening, with oppositely disposed beveled slopes whereby said edges are adapted to cooperate in reaming when the head is rotated on the end of a tube, a pair of prongs each projecting endwise beyond one of said edges for cooperating to straddle a nipple and a nut thereon and engage projections on the nut, and a centering projection between the prongs adapted to enter the nipple and guide the head thereon.

4. A combined wrench and reamer as claimed in claim 3, in which the opposed surfaces of the centering projection and the prongs are rounded to facilitate engagement with an internal cylindrical surface and projections on a nut respectively.
